UNITED STATES PATENT OFFICE.

WILLIAM WECKWERTH AND FRED C. CONRAD, OF HOQUIAM, WASHINGTON.

LUBRICATOR.

1,171,681.

Specification of Letters Patent. Patented Feb. 15, 1916.

Application filed March 1, 1915. Serial No. 11,286.

To all whom it may concern:

Be it known that we, WILLIAM WECKWERTH and FRED C. CONRAD, citizens of the United States, residing at Hoquiam, in the 5 county of Chehalis and State of Washington, have invented certain new and useful Improvements in Lubricators, of which the following is a specification; reference being had to the accompanying drawings.

10 This invention relates to new and useful improvements in lubricating devices and more particularly to what is known in this art as gravity feed lubricators, the main object of the present invention being the 15 provision of a lubricator consisting of a body having therein a tube which extends beneath the body and is provided therein with a wick extending through the tube and into the body which contains the lubricant, 20 thus conveying the lubricant from the body down through the tube, on to the parts to be lubricated.

Another object of the present invention, is 25 the provision of a device of the above character which will possess advantages in points of efficiency and durability, is inexpensive to manufacture and, at the same time, is simple in construction and operation.

With the above and other objects in view, 30 the invention consists in the novel features of construction, combination and arrangement of parts as will be hereinafter referred to and more particularly pointed out in the specification and claims.

35 In the accompanying drawing forming a part of this application, Figure 1 is a side elevation of a lubricator constructed in accordance with our invention. Fig. 2 is a longitudinal sectional view of the same; and 40 Fig. 3 is a detail perspective view of the wick supporting member.

In carrying out our invention, we provide 45 a cylindrical body member 1 which is formed of sheet metal and is provided with an open upper end. Extending through the inner end of the body, centrally thereof, is a discharge pipe 2, one end of said pipe extending outwardly beyond the bottom of the body 1, while the other end thereof extends 50 into the body a suitable distance. The upper edge of the body 1 is provided with a beading upon its outer face, as shown at 3, the purpose of which will be hereinafter more fully set forth.

55 Removably arranged upon the upper open end of the body 1, is a cover 4 having a

downwardly depending annular flange 5 adapted to be inserted within the upper open end of the body and extending outwardly beyond the flange 5, is a horizontal flange 6 60 which is adapted to bear upon the upper edge of the body 1 and the beading 3 to support this cover 4 in its operative or closed position. From this it will be apparent that when it is desired to fill the cylindrical body 65 1 with the lubricant, the cover 4 can be quickly and readily removed by engaging an instrument beneath the flange 6. Extending through the tube 2, is a wick 7, the one end of which projects slightly beyond the outer 70 end of the tube 2, while the inner end thereof extends into the body of the cylinder 1 to absorb the lubricant therein and by capillary attraction, carry the same to the outer or lower end of the tube where it is deposited on the parts to be lubricated. 75

Upon the inner or upper end of the tube 2, we have provided a sleeve 3 and formed integral with this sleeve, is an arcuate extension 9 which is preferably U-shaped in 80 cross section and which forms a support for the wick as it passes into the upper end of the tube 2, thus preventing the wick from cramping or bending, which would stop the flow of the lubricant. The tube or pipe 2 85 is provided adjacent its outer or lower end with a slot 10 whereby a sharp instrument may be inserted therethrough when it is desired to pull the wick out as it wears off at the outer end thereof. 90

From the above description taken in connection with the accompanying drawing, it will be readily apparent that in placing our improved lubricator in position, the body 1 is supported upon the bearing and the tube 2 extended into the bearing so that the wick 95 will engage the surface to be lubricated. The body 1 is then filled with a lubricant, any form of oil being used, and as the pipe 2 extends downwardly below the body 1, the capillary attraction will cause the oil to pass downwardly through the wick 7 on to the parts which are to be lubricated. It will also be noted that by having the extension 9 of the sleeve 8 arcuate in form, it will prevent the wick from becoming cramped or from bending, so as to prevent the flow of oil through the wick. It will also be apparent 100 that our device is extremely simple in construction and can be manufactured and placed upon the market at a comparatively 105 low cost. 110

While we have shown and described the preferred form of our invention, it will be obvious that various changes in the details of construction and in the proportions may be resorted to for successfully carrying our invention into practice, without sacrificing any of the novel features or departing from the scope of the invention, as defined by the appended claims.

Having thus described our invention, what we desire to claim as new and secure by Letters Patent, is:-

1. A lubricator including a body having an open upper end, a beading extending around the open end thereof, a cover having a downwardly depending flange adapted to extend in the body, a horizontal flange adapted to engage over the beading to support the cover, a tube extending centrally through the bottom of the body, said tube extending into the body at a point adjacent the top thereof, a sleeve upon the upper end of the tube, an arcuate supporting arm substantially U-shaped in cross section formed integral with said sleeve, and a wick arranged within the body and extending down through the tube, said wick being adapted to be arranged over the arcuate supporting arm, and said tube being provided with an elongated slot at a point adjacent its lower end, whereby an instrument may be inserted therethrough to adjust the wick within the tube.

2. A lubricator including a body having an open upper end, a beading extending around the open end thereof, a cover having a downwardly depending flange adapted to

extend in the body, a horizontal flange adapted to engage over the beading to support the cover, a tube extending centrally through the bottom of the body, said tube extending into the body to a point adjacent the top thereof, a sleeve upon the upper end of the tube, an arcuate supporting arm substantially U-shaped in cross section formed integral with said sleeve, and a wick arranged within the body and extending down through the tube, said wick being adapted to be arranged over the arcuate supporting arm, and said tube being provided with an elongated slot at a point adjacent its lower end, whereby an instrument may be inserted therethrough to adjust the wick within the tube.

3. A device of the character described including a container, a tube extending into one end of the container, a wick arranged within the tube, and a wick support disposed at the inner end of the tube and including a radially extending outwardly and downwardly curved wick supporting arm, the arm being transversely curved to form a seat for the wick.

In testimony whereof we hereunto affix our signatures in the presence of two witnesses.

WILLIAM WECKWERTH.
FRED C. CONRAD.
